UNITED STATES PATENT OFFICE.

ALONZO L. SWEET, OF NORWICH, CONNECTICUT, ASSIGNOR TO THE BACON ARMS COMPANY, OF SAME PLACE.

FIRE-ARM.

SPECIFICATION forming part of Letters Patent No. 243,993, dated July 5, 1881.

Application filed April 19, 1881. (No model.)

To all whom it may concern:

Be it known that I, ALONZO L. SWEET, of Norwich, in the county of New London and State of Connecticut, have invented a new and useful Improvement in Revolving Fire-Arms; and I do hereby declare that the following is a full, clear, and exact description of the same.

My invention relates to an improvement in the construction of fire-arms, and more especially to that of revolving pistols.

The invention has more particular reference to the construction and attachment of the locking plate which closes the opening in the side of the pistol, by which access is gained to the parts which would be otherwise concealed. These plates have been made in various shapes, one form being a round plate having a central opening, through which the screw-pivot for the hammer was passed, and which was held firmly in position flush with the side of the arm by tightening the screw in bringing the parts into place.

In a patent granted to Wm. H. Bliss, April 23, 1878, was shown a circular locking-plate for pistols differing from the form just mentioned in having the screw-bolt or pivot permanently attached to its center, and having an outside slot or perforation for the screw-driver, forming, practically, a screw with an enlarged flat head. Both these devices are open to serious objections. In either case the removal of the plate for the inspection of the parts is impossible without first or simultaneously removing the pivot-bolt which holds the hammer in position, and the removal of this pivot both permits the hammer to drop from its position relative to the other parts and causes some unavoidable trouble in its accurate readjustment. Further, the pivot-bolt by constant wear in its end bearings becomes loose and shaky and impairs the accuracy of the hammer and the force of the blow.

My invention consists, first, in an improved construction by which the locking-plate may be removed without detaching the pivot-bolt, and thus complete access to the interior of the pistol given without in any way altering or affecting the position of the other parts; and,

further, in providing a bearing for the pivot-bolt, which may be tightened, and prevents such bolt from wearing at the ends.

The invention is illustrated in the accompanying drawings, in which Figure 1 is a side view with the plate removed. Fig. 2 is a cross-section taken centrally through the pivot-bolt on line *xx*, Fig. 1. Fig. 3 is a separate view of the locking-plates.

In these drawings, A represents the stock of a pistol, B B' the ordinary side plates, and C the hammer. This hammer is mounted on a screw-bolt, D, which passes through it and is screwed into the side plate, B', and is finished off on the outside flush with the face of such side plate. In the opposite side plate, B, is a circular opening, *c*, the center of which is opposite the head of the bolt D, and this bolt projects outwardly into the opening a distance about equal to half the thickness of the side plate. The edge of the plate B, where cut away to form the opening, is tapped with a screw-thread.

The locking-plate is represented by E and separately in Fig. 3. It is a flat circular metallic plate of the same thickness as the side plates, and its edge is provided with a thread corresponding to that in the side plate. On the inner side of the plate E is a circular recess, 2, and on the outside there may be a slot, 3, which may or may not extend entirely through the thickness of the metal of which the plate is composed.

In constructing this pistol the screw-bolt is first passed through the hammer into the plate B' and tightened up. The locking-plate is then inserted into the opening *c* and tightened by screwing down. When the plate is tightened the projecting end of the bolt D enters the recess 2 and bears firmly upon the circumference of such recess, and it is evident that while the said recess provides a firm bearing for the bolt-head the complete removal of the plate E does not change the position of the parts. It is also evident that any looseness or shaking in the bolt can be corrected by screwing down the plates and tightening the end bearings.

I am aware that the side plate of a pistol has been provided with a pivot-bolt for the hammer, the end of such bolt being screw-threaded to engage with a plate fitting a circular opening in the opposite side plate. I am also aware that it is not broadly new to cut a screw-thread on the periphery of a circular plate, and do not, therefore, claim these constructions.

10 Having thus described my invention, what I claim is—

In a pistol, the combination of the side plate, B', having the bolt D secured thereto, said bolt

forming the pivot for the hammer, the side plate, B, and the locking-plate E, having screw-threaded periphery to engage with a circular screw-threaded opening in side plate, B, the said locking-plate being provided with a recess, 2, to receive the end of the bolt D.

15 In testimony whereof I have signed my name to this specification in the presence of two subscribing witnesses.

ALONZO L. SWEET.
